WALL CASE

Percy E. Stiles, Beloit, Wis.

Application April 20, 1935, Serial No. 17,443

7 Claims. (Cl. 312—141)

This invention relates to cases, and has special reference to a wall case of novel construction, particularly adapted for use by organizations such as churches, lodges, schools and the like, as an aid in the secretarial, financial, and publicity work of the organization.

A principal object of the invention is the provision of a wall case or cabinet for centralizing the secretarial activity of an organization, such as a church, providing facilities for the members to carry out a large part of such work themselves, and providing discreet publicity for the status of the individual members in their duties toward the organization.

Another object of the invention is the provision of a secretarial wall case having individual pockets for each of the members, a plurality of pockets for holding blank information cards, means for the deposit of the information cards and the material from said individual pockets for delivery to the secretary of the organization, and closures for the case arranged to act as bulletin boards when the case occupies its open position.

Another object of the invention is the provision of a case of the character described having provision for convenient change of the capacity of the case to care for changes in the membership of the organization.

A further object of the invention is the provision of a wall case of the character described so constructed as to be of relatively thin cross-section and rest in close proximity to the wall, constructed substantially entirely of sheet metal and in such manner as to provide maximum usable space with a minimum overall dimension, and arranged in interfitting sections to allow for change in the capacity of the case.

Other objects and attendant advantages will become apparent to those skilled in the art from the following description and the accompanying drawings, in which—

Figure 1 is a front elevation of a case embodying my invention;

Fig. 2 is a top view;

Fig. 3 is a section on the line 3—3 of Figure 1;

Fig. 4 is a face view of the pocket member prior to the forming thereof;

Fig. 5 is a view similar to Fig. 4 of the formed pocket member;

Fig. 6 is a section on the line 6—6 of Fig. 5;

Fig. 7 is a fragmentary perspective view partly in section showing an upper corner of the case;

Fig. 8 is a fragmentary perspective view partly

in section showing the connection between the parts of two sections;

Fig. 9 is a fragmentary perspective view of a divider strip;

Fig. 10 is a fragmentary perspective view of one of the cover molds;

Fig. 11 is a fragmentary perspective view of one corner of the frame;

Fig. 12 is a fragmentary perspective view of one of the joiner iron members which serve to hold the various sections together;

Fig. 13 is a section on the line 13—13 of Figure 1;

Fig. 14 is a section on the line 14—14 of Figure 1;

Fig. 15 is a section on the line 15—15 of Figure 1;

Fig. 16 is a section on the line 16—16 of Figure 1, and

Fig. 17 is a section on the line 17—17 of Figure 1.

The invention contemplates a case adapted to be hung upon the wall or other suitable supporting structure adjacent the entrance of the meeting place of an organization and in a conspicuous place, so that the members will naturally approach the same upon entering or leaving the meeting place. The case further contemplates a plurality of sectional units which may be combined in any number required in order to make a complete case. These sectional units are generally of three kinds which may be designated as "personal sections", "general sections" and "bulletin sections." A typical embodiment of the invention is shown in Figure 1, wherein two personal sections, one general section and two bulletin sections are combined to form a case in the manner contemplated.

Referring first to Figs. 7-14, inclusive, showing the structure of the personal section, the numeral 21 designates a rectangular frame formed of so-called "square root" angle iron, that is, angle iron in which the inner angle comes to a sharp right angle for close fit with abutting elements. The frame has portions 22 and 23 forming an internal right angle, the portion 23 being notched to form the corners, as shown at 24. A back plate 25, consisting of a sheet of sheet metal, is positioned in the frame on the portion 23 and suitably fastened thereto preferably by spot welding. Dividers 26, in this instance, eleven in number, are positioned within the frame and extend laterally and vertically thereacross in parallel spaced relation for the purpose of forming sides for the pockets presently to be described. The

dividers bear against the side portions of the frame and are preferably spot welded thereto as shown at 21. The general form of the dividers is best shown in Fig. 9, from which it will be seen that each of the dividers has a plurality of longitudinally spaced slots 28 forming angularly projecting fingers 29. Positioned within these slots 28 are longitudinally extending pocket members, designated generally by the numeral 31, the pocket members being laterally spaced and lying in parallel relation at an acute angle with respect to the back plate 25. The pocket members 31 are therefore spaced a distance equal to the width of the fingers 29, the slots 28 and fingers 29 acting to support the pocket members with such uniform spacing, and the fingers 29 serving to separate the space between the pocket members into a plurality of separate pockets.

The pocket members are formed as shown in Figs. 4-6 by blanking out a sheet metal piece having the shape characteristics shown in Fig. 4 and having spaced slots 32 of a spacing equal to the spacing of the dividers 36, the upper end of the slots being adapted to seat in the lower end of the slot 28 of the divider. The sheet is also formed with spaced slots 33 adapted to provide windows for each of the pockets and spaced slots 34 above the slots 33 for the purpose of providing an open edge on the top of the pocket member for insertion of a ticket bearing the name and address of the member. The stamped sheet is also provided with spaced laterally disposed ribs 35 and longitudinally formed ribs 36. The stamped sheet is bent back upon itself along the line formed by the slots 34 as shown in Figs. 5 and 6 whereby the ribs 35 and 36 come into contact with the back side of the sheet forming ticket receiving chambers 37, the front sides of which are opened by the window slots 33, and the upper edges of which are opened by the slots 34. This provides a convenient manner in which the tickets may be inserted and removed from the chambers. The lower edge of the pocket member is angularly formed, as shown at 38, so as to about 45 against the back plate 25 and cause the member to extend upward in properly spaced relation with the adjacent pocket member and at a proper angularity with respect to the back plate. The pocket members are attached to the back plate by means of the formed angular portions 38, preferably by spot welding the same to the back plate.

The lower pocket member is formed somewhat differently in order to provide interlocking means for the attachment of a lower personal or general section. This is shown in Fig. 14 from which it will be seen that the lower pocket member 39 has its upper edge bent forwardly upon itself as shown at 41 to provide an overhanging bead and a flat portion 42, the forward edge of the member being spot welded to the front side of the pocket member as shown at 43. The lower end of the pocket member is attached to the frame by means of a bracket 44.

Cover molds such as shown in Fig. 10 constitute a trim for the side edges of the case section. These molds comprise sheet metal pieces having sides 45, a top 46 provided with a bead 47 at the junction of the sides and top and provided with 70 downwardly projecting fingers 48 adapted to slip into the space between the pocket members 31, as best shown in Fig. 7, thereby concealing the junction between the frame and the pocket members and covering the sharp edges formed at this 75 point. A cover sheet having a top edge 49 and a

face 51, the lower edge of which is beveled downward as shown at 52, is adapted to be positioned at the top of the case as best shown in Fig. 13 so as to cover the space between the upper pocket member and the top edge of the frame. This 5 cover sheet rests below the cover mold, as best shown in Fig. 7, and has a bead 53 adapted to abut against the upper edge of the cover mold so as to provide a neat mold design. The cover molds are preferably attached to the frame by 10 means of screws 50, and because of their position above the cover plate 51, act to hold all of the trim in position on the frame.

The lower section of the personal section unit is substantially identical with that above described, with the exception that the upper pocket member 54 thereof (Fig. 14) is positioned at the upper edge of the frame and projects thereabove a short distance. A flange member designated generally by the numeral 55 is attached to the 20 back of the pocket member 54 and extends upwardly as shown in this figure to be received under the depending bead 41 of the upper personal section, thereby concealing the junction between the two sections of this unit. The upper 25 side of the frame and the lower section abuts the lower edge of the upper section as shown in Fig. 14. The two sections of the personal section unit are held together by means of square root 30 angle members designated generally by the numeral 56 adapted to be positioned at either side of the case and be secured thereto by means of the bolts 50 in the two sections of this unit which thereby hold the two sections together in the relationship shown in Figs. 8 and 14.

The general section, indicated by the numeral 57, is constructed in the manner best shown in Figs. 15-17, and includes a centrally disposed deposit box 58, literature boxes 59 and 61 disposed on opposite sides of the deposit box 58, and a plurality of pockets for information cards, arranged behind the deposit box 58 and the boxes 59 and 61. The general section has a longitudinally extending angle iron member 62 which serves for the attachment of the section to the personal section unit, bolts or screws 63 serving to hold the member 62 against the lower side of the personal section frame. Extending along the upper edge of the general section, and attached to the angle iron member 62 is a flange member 64, the upper edge of the flange member projecting upward for reception beneath the depending bead 41 on the lower pocket member of the personal section unit so as to conceal the space therebeneath. The flange member 64 extends downward and has a rearwardly extending flange 65 at its lower edge behind the deposit box 58 and a forwardly extending ledge 66 on opposite ends thereof behind the boxes 59 and 61, terminating in a depending edge 67. The back 68 of the deposit box 58 is spot welded to the flange 65 and toward its top extends forwardly to form the bottom 69 of a plurality of pockets for information cards, as indicated at 71. The back member then extends upwardly as shown at 72 to form the front wall of the pocket members 71 and at its upper edge is beaded as shown at 73 to interlock with the forward part of the deposit box, as will presently be described. The lower portion 70 of the back member 68 is inclined outwardly and downwardly as shown at 74 and is adapted for attachment at the forward end to the front side of the deposit box thus forming a sloping bottom 75 for the deposit box. A single piece of sheet metal

forms the front, top and sides of the deposit box, the front being indicated by the numeral 75, the top by 76, and the sides by 77. The top 76 of the box is flanged upwardly as shown at 78 for reception under the bead 73 whereby the upper edge of the box is attached to the back thereof. The top also has a slot 70 to allow for the deposit of cards and other material in the box. The lower edge of the front 75 is attached to the bottom 74 by means of spot welding or other suitable means. The side edges of the back member 68 are attached to the side walls 77 of the deposit box by spot welding or other suitable means of attachment. The front 75 of the deposit box carries a sheet metal door 79 pivoted thereto as indicated at 81 and carrying a lock 82 acting to engage the bottom 74, as shown in Fig. 16 to retain the door in a closed position.

The front 83, bottom 84 and back 85 of each of the magazines or literature holding boxes are formed from a single piece of sheet metal, the back portions being provided with beads 86 for a purpose which will presently appear. One edge of these elements is attached to the deposit box by means of flanges 87 spot welded or otherwise suitably connected thereto. The opposite edges are spot welded to end pieces 88 and 89 which extend rearwardly to the plane of the back of the case and upward to the lower edge of the personal section unit as shown at 91. A plurality of strips 92 extend between the backs of the boxes and the index sheet 64 to separate the space into pockets for holding information cards. The strips are secured in position by means of fingers 93 and 94, the former of which are concealed by the beads 86, as shown in Fig. 15. Shelves 95 and 96 are positioned in the boxes and carry racks 97 and 98 engaging pinions 99 and 101 for raising and lowering the shelves to accommodate papers of different lengths in the boxes. The pinions are actuated by means of knobs 102 and 103 on the sides of the case.

The bulletin section comprises a combined door and bulletin board adapted to be secured on the personal section unit as shown in Figure 1 when a two-part personal section unit is employed. The bulletin sections may be made the same size and shape as the personal sections so that by hinging one on either side of a two section personal section unit a complete closure may be had. Likewise, where only a single section personal section unit is employed, a single bulletin section may be hinged at the top and thereby form a complete closure.

The bulletin section preferably comprises a body 104 of wood or other material capable of taking thumb tacks desirably having an outer covering 105 of sheet metal formed around the edges of the body as shown at 106. Folds may be formed near the edges of the body as shown at 107 to form a trim for the bulletin sections. Hinges 108 at one edge are attached to joiner irons 56 and serve to carry the bulletin sections on the personal section unit for rotation between an open position as shown in Figure 1 and a closed position covering the face of the personal section unit.

The manifold advantages of my improved case will doubtless have become apparent. It provides a unitary case concentrating the secretarial, financial and publicity activities of the organization and providing means whereby the members may be caused to carry out a large part of the secretarial activities of the organization. The pockets, for example, are adapted to contain cards

or booklets for each member outlining the activities of the member and providing spaces to be filled in so as to keep a record of the attendance of the member, the performance of regularly constituted duties toward the organization, and the payment of contributions pledged to the organization. Likewise, the pockets provide means whereby the status of the member may be given a certain amount of publicity by making the cards of such length that they extend upward over the name plate, and providing on the card in this exposed area indicia for showing the status of the member with regard to his duties toward the organization, such, for example, as his contributions and attendance.

The case also provides means whereby these record cards may be deposited for delivery to the secretary of the organization, the cards being deposited in the locked deposit box 58. Separate pockets are provided for holding information cards which, when filled out, are dropped into the deposit box. The case also provides literature boxes adapted to contain literature to be distributed by the organization or periodic instructions to the members as to the use of the individual cards or the information cards.

Means are provided whereby the personal section unit may be covered when the cabinet is not in use, to prevent soilage of the personal cards through prolonged exposure and to prevent access thereto by meddlers. This consists of the bulletin sections which act when in their open position as bulletin boards upon which notices may be tacked or written in the usual manner. When these bulletin sections are swung to the closed position, the bulletin boards and the personal section are both enclosed and protected.

While I have thus described and illustrated a specific embodiment of my invention, I am aware that numerous alterations and changes may be made therein and I do not wish to be limited except as required by the prior art and the scope of the appended claims, in which—

I claim:

1. The combination in a secretarial wall case of a personal section comprising a frame, a plurality of transverse dividers, a plurality of longitudinally disposed pocket members, and a plate adapted to engage one side of the frame and be received between said dividers and the pocket member adjacent said side of the frame to conceal the junction between the frame and the dividers.

2. The combination in a secretarial wall case of a personal section comprising a frame, a plurality of longitudinally disposed pocket members having their ends substantially abutting against one side of said frame, and a mold member shaped to cover the sides of said frame and having fingers shaped for entry between said pocket members whereby to conceal the junction between the pocket members and the sides of the frame.

3. In a secretarial wall case, a personal section comprising in combination a frame, a plurality of divider strips of sheet metal parallelly secured in said frame and having spaced fingers, a plurality of pockets, said pocket members being formed along one side to provide bottoms for said pockets and for attachment to said frame, each of said pocket members also being bent back upon itself and ribbed along the opposite edge thereof to form card receiving chambers, said members also being slotted to provide windows in said chamber for viewing cards positioned

therein, and trim members shaped and positioned to cover the junction between the frame and the ends of the divider strips and the pocket members.

- 5 4. In a secretarial wall case for public use having a personal section unit, the combination therewith of a general section including a pair of laterally spaced rectangular open top boxes for holding literature on edge, adjustable bottoms 10 in said boxes, a vertically disposed rack attached to each of said bottoms substantially midway between the ends thereof, pinions rotatably carried on said general section in engagement with said racks, and means for actuating said pinions from points on the sides of said general sections for adjusting the elevation of said bottoms to adapt the boxes to different sizes of literature.
- 5 5. The combination in a secretarial wall case of 20 a personal section comprising a frame, a plurality of strips extending longitudinally of the frame and forming pocket members, a plurality of divider strips extending across said frame, formed of sheet metal and parallelly secured to the upper and lower sides of the frame, said divider strips having spaced notches and fingers along the outer edge to support, separate and

partition said pocket members to form a plurality of separate pockets.

6. The combination in a secretarial wall case of a personal section comprising a frame, a plurality of divider strips extending across said frame, and of card pocket shelves of sheet metal, embossed and folded back along the upper edge to form name card chambers, each of which has a punched opening forming a window for displaying the name on the card and a slot at the 10 top for inserting and removing the card, the lower part of said shelves being slotted at regular intervals to interfit into notches in the divider strips, and being formed with reverse bends to provide bottoms for card pockets and flanged to 15 attach to the back sheet.

7. The combination in a secretarial wall case of a plurality of doors, two or more personal sections having frames held together by joiner irons, which consist of a square root angle iron on each 20 side of the sections of sufficient size and strength to hold them together as one case and carry the doors, and means for fastening the said joiners in turn to the frame of the sections in both side and back arms of the angle iron. 25

PERCY E. STILES.
